UNITED STATES PATENT OFFICE.

EMIL M. KNOTHE, OF SEATTLE, WASHINGTON, ASSIGNOR TO EMELINE KNOTHE, OF SEATTLE, WASHINGTON.

CAR-FENDER.

1,214,175.

Specification of Letters Patent. Patented Jan. 30, 1917.

Application filed November 15, 1916. Serial No. 131,356.

To all whom it may concern:

Be it known that I, EMIL M. KNOTHE, a citizen of the United States, and resident of the city of Seattle, county of King, and State 5 of Washington, have invented certain new and useful Improvements in Car-Fenders, of which the following is a specification.

My invention relates to car fenders and comprises certain novel parts and combinations of parts which will be described and particularly pointed out in the claims.

The object of my invention is to improve upon fenders of the class shown in my prior Patent No. 1,189,832, issued July 4, 1916.

15 The accompanying drawings show the preferred construction.

Figure 1 is a vertical section taken longitudinally of the car showing the fender and its operating mechanisms. Fig. 2 is a bottom plan view of the fender apron and the mechanism for operating the same located beneath the car. Fig. 3 is a front elevation showing parts of both the fender and the car front broken away to better show the relation of the parts. Fig. 4 is a vertical section taken on a plane extending lengthwise of the car showing the pivotal support of the fender and the different positions occupied thereby. Fig. 5 is a vertical section showing 20 the mechanism by which the position of the fender is controlled. Fig. 6 is a vertical section showing in detail the hinge of the fender and the support therefor, and Fig. 7 is a vertical section showing a modified construction for the valve actuating mechanism.

25 This fender, in the general character of its structure and the manner of operating it, clearly resembles that shown in my prior application above referred to. The points 40 wherein the construction, here illustrated, is the same as in the fender shown in said application, will not herein be described in detail.

The fender apron 1 is connected to a couple 45 of cast arms 11, which latter arms are so shaped that they extend upwardly and to the rear from the bar 12 which forms the rear edge of the fender apron. These carrying arms 11 are pivoted at 13 from blocks 50 15, which are adapted to be secured at variable elevations to the lower part of the suspension bars 2, which suspension bars extend upwardly to the rear of the bumper B and are pivoted at 21, which point is preferably located at or near the level of the

floor of the car. The carrying arms 11 have rearward projections 14 which are engaged by pins 31 which extend through the flanges of the block 15 to thereby hold the fender apron in its fixed position. By withdrawal 60 of the pins 31 the fender apron may be thrown up into vertical position, as is shown by the dotted lines in Figs. 1 and 6. In this raised position the reinsertion of the pins 31 cause them to engage the opposite side of 65 the short arm 14 to thus hold the fender in raised position. The pins 31 are carried by arms 30 which are secured upon a rod 3, which extends transversely of the car, and is provided at one end with a side projection 33, by which it may be engaged to reciprocate to thereby withdraw and insert the pins 31. Spring 32 acts to hold the bar 3 in locking position. This construction is similar to that shown in my prior application. 70 75

The fender is normally held forwardly by means of a spring 4, which is placed outside of two telescoping members 40 and 41, the member 40 being pivoted to the lower end of the suspension bar 2, or as an equivalent, 80 to the block 15 carried upon this bar. The tubular member 40 of this combination, has a threaded section upon which is placed adjustable nuts 42, which receive the thrust of the spring 4. The inner member 41 of the 85 telescopic connection is hingedly supported at 43 from the car frame. The initial tension upon the spring 4 may be adjusted by varying the location of the thrust nuts 42. This tension should be such as to normally 90 maintain the fender apron 1 in its extreme forward and upward position. It is intended that this apron be capable of a certain amount of swing upon the pivot axis 21 without actuating the valve by which the 95 power cylinder is supplied with air to draw the fender backward and downward. This feature is the same as that shown in my prior patent above noted.

The valve by which the air is controlled 100 is shown at A, this being similar in all its essential respects to that shown in said application. The air connections between the cylinder and said valve and with the motor-man's controlling lever remain the same, and their detail description is not believed to here be necessary.

The manner of connecting the valve operating mechanism with the fender apron for automatic action thereby, is somewhat 110

different from that shown in my prior patent above noted. A shaft 5 which extends transversely of the car has two arms 50 secured thereto and extending downward. 5 These arms have slots which receive the ends of rods 52, the slot being of such length that the required angular movement of the arms 50 will not cramp the rods 52 therein. The other ends of rods 52 are pivotally connected to the suspension bars 2, and springs 53 are placed about the rods 52 and bear against the arms 50 and against an adjustable thrust nut 54 carried by the rod 52. 10 The initial tension upon spring 53 is adjusted so as to overcome the resistance to the rocking of the shaft 5, when the downward and backward swing of the fender has reached a predetermined point. When this point is reached, the oscillation of the shaft 20 5, acting through the arm 51, will draw down rod 55 which is connected to the valve A so as to operate this to admit air to cylinder P. The cylinder P has a piston 6 therein, the outer end of which is slotted to receive the end of lever 60, which is pivoted at 61 and is connected by its other end to a rod 62 which, in turn, connects it with bar 63, which extends between and connects the two blocks 15, upon which the fender 30 apron is pivoted. Admission of air to cylinder P forces the piston outward and, by the above connecting means, draws the fender apron backward and downward until its forward end rests upon the ground, to 35 the position shown by the dot and dash line in Fig. 4. Extending upward from adjacent the rear edge of the fender apron is a guard frame 19. This is provided with slots 18 in its lower edge, so positioned as 40 to receive the fender carrying arms 11 when the fender is swung to its upper position. It is also provided with an opening 17 which is located in front of the draw bar and fender apron 1 is also provided with an opening 45 10 in position to register with the opening 17 when the fender is in raised position.

Maintained upon the suspension bars 2, 50 are two bars 7, which are pivotally connected at 70, and are connected at their rear end by a transversely extending rod 71, to which is connected a rod 72 extending upwardly and provided with a turn buckle 73, or other means by which its length may be 55 adjusted. The upper end of this rod is bent laterally, so that it may be secured to an arm of a bell-crank lever 75, the other arm of which is connected by a link 76 with an arm 77, which is connected to move with 60 the operating lever 78.

Mounted upon the dash D is a plate 74 having a slot therein which will receive the bent end of the rod 72, while the latter is not connected with the lever 75. The bar 7, 65 which is pivoted to the suspension bars 2,

has its forward end turned up to form a shallow notch 79, which is so placed as to engage with the forward edge of the bumper B, when the fender is in its extreme forward position and when the valve controlling handle 78 is in its normal position. This device is intended for use under conditions where the automatic action of the fender is to be eliminated. This is desirable in case where snow is upon the ground 75 to such an extent as to offer a backward resistance to the fender. Without some provision of this sort the resistance offered by the snow would be sufficient to trip the valve and cause the fender to be depressed. 80 By connecting the locking bars 7 with the valve operating handle 78, locking bars 7 will be released upon manual application of air to the cylinder P, thus offering no resistance to the manual operation of the 85 fender, but cutting out the automatic feature of its operation.

The spring 53, which transmits the backward push from the fender suspension bars 2 to the arm 50, acts under compression. 90 In Fig. 7 I have shown a modification in which an equivalent spring acts under tension. This spring 56 has one end anchored at 57, and the other end secured to the arm 50, and is normally under tension. Rod 95 58 has a pin 59 which engages with the rear surface of the arm 50, the front end of rod 58 being secured to the suspension bars 2. The result of this is substantially the same as of the other form of construction. The 100 backward swing of the fender beyond a certain point permits the spring 56 to open the valve A and admit air to the operating cylinder P.

Having thus described my invention, what 105 I claim as new, and desire to secure by Letters Patent of the United States of America, is:—

1. In a car fender, in combination, a fender apron having carrying arms rigid therewith and extending upwardly and rearwardly from its rear edge, pivot supports for said arms distant from the rear edge of the fender apron, and a guard frame extending upward from adjacent the rear edge 115 of the fender apron and having slots for the reception of the fender-carrying arms when the fender apron is raised.

2. In a car fender, in combination, a fender apron having carrying arms rigid therewith and extending upwardly and rearwardly from its rear edge, pivot supports for said arms distant from the rear edge of the fender apron, and a guard frame extending upward from adjacent the rear edge 125 of the fender apron and having slots for the reception of the fender-carrying arms when the fender apron is raised, the guard frame and the fender apron having openings which 130 register with each other and with the car

coupler when the fender apron is in raised position.

3. In a car fender, in combination, a fender apron having carrying arms rigid therewith and extending upwardly and rearwardly from its rear edge, pivot supports for said arms distant from the rear edge of the fender apron, and a guard frame extending upward from adjacent the rear edge of the fender apron and having slots for the reception of the fender-carrying arms when the fender apron is raised, the carrying arms and the members to which they are pivoted having interlocking members engageable to hold the fender apron in either raised or lowered position.

4. In a car fender, in combination, fender suspension members located back of the bumper member of the car frame and pivoted by their upper ends above the bumper to swing parallel with the length of the car, fender carrying arms fixed to the rear edge of the apron frame and having pivotal supports from said suspension members located upwardly and rearwardly of the rear edge of the fender frame.

5. In a car fender, in combination, fender suspension members located back of the bumper member of the car frame and pivoted by their upper ends above the bumper to swing parallel with the length of the car, a block carried by the lower end of each of said suspension members and vertically adjustable thereon, and a fender apron having carrying arms pivoted upon said blocks at points upwardly and rearwardly of the rear edge of the fender apron.

6. In a car fender, in combination, fender suspension members located back of the bumper member of the car frame and pivoted by their upper ends above the bumper to swing parallel with the length of the car, fender carrying arms fixed to the rear edge of the apron frame and having pivotal supports from said suspension members located upwardly and rearwardly of the rear edge of the fender frame, and springs acting to normally maintain said suspension members in forward position.

50 7. In a car fender, in combination, fender suspension members located back of the bumper member of the car frame and pivoted by their upper ends above the bumper to swing parallel with the length of the car, fender carrying arms fixed to the rear edge of the apron frame and having pivotal supports from said suspension members located upwardly and rearwardly of the rear edge of the fender frame, springs acting to normally maintain said suspension members in forward position, and a power mechanism adapted to be thrown into action to swing said suspension members rearwardly.

65 8. In a car fender, in combination, fender suspension bars extending vertically back

of and pivoted above the bumper to swing from front to rear, a fender apron supported from the lower ends of said suspension arms, and springs acting to normally hold said suspension bars toward the forward part of their swing.

9. In a car fender, in combination, fender suspension bars extending vertically back of and pivoted above the bumper to swing from front to rear, a fender apron supported from the lower ends of said suspension arms, springs acting to normally hold said suspension bars toward the forward part of their swing, retracting mechanism for the fender, and means for throwing the retracting mechanism into action by a movement of the fender apron backward of a predetermined point.

10. In a car fender, in combination, fender suspension bars extending vertically back of and pivoted above the bumper to swing from front to rear, a fender apron supported from the lower ends of said suspension arms, springs acting to normally hold said suspension bars toward the forward part of their swing, and a lock, releasable by hand and adapted to hold the fender in its extreme forward position.

11. In a car fender, in combination, a fender apron, means for supporting this apron to permit its moving downward and backward, means yieldingly supporting the fender apron in advanced position, a power retracting means automatically brought into action by a backward movement of the fender apron beyond a predetermined point, means for manually throwing said retracting mechanism into action, and a lock adapted to prevent the action of the automatic retracting means and connected to the means for manually actuating the retracting means to be released by the operation thereof.

12. In a car fender, in combination, a fender apron, suspension bars connecting with the rear part of said apron to swing from front to rear, springs normally holding the fender apron forwardly, a power actuated means for retracting the fender, means for applying said power means by the backward movement of the fender apron beyond a predetermined point, a means for manually throwing said power means into action, a catch carried by the suspension bars and adapted to engage a fixed member to prevent backward movement of the fender, and means for optionally connecting said catch with the means for manually controlling said power retracting means to release said catch by the same movement which throws said power means into action.

13. In a car fender, in combination, a fender apron and supporting means therefor permitting movement from front to rear, means for yieldingly holding the fender forwardly, a power device for retracting the

fender, normally held out of action, means for throwing said power device into action by backward movement of the fender comprising a spring through which the tripping effort is transmitted.

14. In a car fender, in combination, fender suspension bars pivoted at their upper ends to swing from front to rear, a fender apron carried by the lower ends of said suspension bars, means operable by the fender for effecting a downward and backward swing of the fender, and a lock adapted when in use to nullify the control by the fender of the means for swinging the fender backward.

15. In a car fender, in combination, fender suspension bars pivoted at their upper ends to swing from front to rear, a fender apron carried by the lower ends of said suspension bars, means operable by the fender for effecting a downward and backward swing of the fender, a lock adapted when in use to nullify the control by the fender of the means for swinging the fender backward, and manually controllable means for actuating the fender swinging means having also a connection with said lock to release it when the fender swinging means is thrown into action.

16. In a car fender, in combination, a fender apron and supporting means therefor permitting a downward, receding movement of the apron, mechanism for applying power to secure such movement, a hand controlled and an automatic means for applying the power swinging mechanism, a lock adapted to prevent swinging of the fender apron and means whereby said lock may be connected for release by the action of the hand controlled member when applying the power swinging mechanism.

17. In a car fender, in combination, a fender apron adapted to be mounted on a car for downward receding movement, two sepa-

rate means for operating the fender apron, 45 and a locking means adapted to prevent the operation of one of said means without affecting the action of the other.

18. In a car fender, in combination, a fender apron and means for mounting it to permit downward receding movement, an automatic and a manually controlled means for securing said movement of the fender apron, a lock adapted to prevent the operation of said automatic means and to be connected with the hand controlled means to be released thereby.

19. In a car fender, in combination, a fender apron, suspension bars connected with the rear part thereof and extending upwardly back of the car bumper, means under control of the apron for swinging the apron into its lower position, auxiliary means for lowering the apron independent of the action of the apron-controlled means, and a lock controlled by the auxiliary means and adapted to prevent the operation of the apron-controlled means.

20. In a fender, in combination, a fender apron, suspension bars extending upward from the rear edge of the apron and pivoted at their upper ends, means for vertically adjusting the connection between the apron and its suspension bars, and means for controlling the position of the fender apron lengthwise of the car.

21. In a fender, in combination, a fender apron, suspension bars extending upward from the rear edge of the apron and pivoted at their upper ends, means for vertically adjusting the connection between the apron and its suspension bars, springs normally holding the fender forwardly, and means for applying power to draw the fender backward.

Signed at Seattle, Washington, this 9th day of November, 1916.

EMIL M. KNOTHE.
